UNITED STATES PATENT OFFICE

162,736

KEYHOLE SAW

Robert W. Huxtable, Greenfield, Mass., assignor
to Millers Falls Company, Greenfield, Mass., a
corporation of Massachusetts

Application January 19, 1950, Serial No. 7,318

Term of patent 14 years

(Cl. D54—13)

To all whom it may concern:

Be it known that I, Robert W. Huxtable, a citizen of the United States, residing at Greenfield, in the county of Franklin, and State of Massachusetts, have invented a new, original, and ornamental Design for a Keyhole Saw, of which the following is a specification, reference being had to the accompanying drawing, forming a part thereof.

Figure 1 is a side elevation of a keyhole saw showing my new design;

Figure 2 is a top plan; and

Figure 3 is an end elevation looking from the right end of the tool as shown in Figure 1.

I claim:

The ornamental design for a keyhole saw as shown.

ROBERT W. HUXTABLE.
